UNITED STATES PATENT OFFICE.

EDWARD F. EDGEcombe, JR., OF INDIANAPOLIS, INDIANA, ASSIGNOR TO MEIER-GAYNOR MFG. CO., OF INDIANAPOLIS, INDIANA, A CORPORATION OF INDIANA.

BOTTLE CAPPER.

Application filed October 30, 1920. Serial No. 420,618.

To all whom it may concern:

Be it known that I, EDWARD F. EDGEcombe, Jr., a citizen of the United States, residing at Indianapolis, in the county of Marion and State of Indiana, have invented a new and useful Bottle Capper, of which the following is a specification.

In the operation of bottle-capping machines the cap is placed upon the filled bottle by the exertion of a substantial pressure through the medium of a spring, acting upon the capping plunger, the common arrangement being one in which the capping plunger, after association with the bottle and its cap, is carried beneath a spring-pressed plunger.

In the operation of such a device, there is unavoidably some variation in heights of the bottles and this variation may be quite considerable. Under such circumstances, if the spring has sufficient resistance to provide an adequate capping pressure for short bottles, the resistance is likely to be too great in the operation of capping tall bottles, and considerable difficulty has heretofore been experienced because of breakage of the taller bottles, or an improper capping of the shorter bottles.

The object of my present invention is to provide means by which automatic compensation may be made for differences in bottle heights, so that the spring pressure exerted in the capping operation will be substantially the same, no matter what the height of the bottle may be, within the range of the apparatus.

The accompanying drawings illustrate my invention. Fig. 1 is a side elevation in partial vertical section, of a capping machine embodying my invention; Fig. 2 a plan in partial horizontal section; Fig. 3 a diagrammatic plan of the coacting bottle-driving wheels which engage the necks of the bottles; Fig. 4 a vertical axial section, on an enlarged scale, of the compensating abutment for the capping spring; Fig. 5 a side elevation in partial vertical section in a plane at right angles to the plane of Fig. 4; and Fig. 6 a sectional detail similar to Fig. 4 and showing a modification.

In the drawings, 10 indicates a suitable base in which is journaled a vertical shaft 11 driven by the gear 12 meshing with a pinion 13 of the driving train 14. Shaft 11 carries a horizontal bottle-supporting disk

15 which is surmounted by a notched wheel 16 which, in turn, is surmounted by a neck-engaging disk 17.

Arranged above disk 17 on shaft 11 is a capping head 18 which comprises a plurality of circumferentially spaced capping plungers 19, each of which is preferably provided at its upper end with a roller 20 which rides upon an annular cam 21. Each capping plunger 19 is formed at its lower end in any well-known manner to perform the capping operation.

Shaft 11 carries a gear 22 which meshes with a gear 23 carried by a shaft 24, said shaft 24 carrying a bottle-engaging notched wheel 25 which cooperates with wheel 16. Shaft 24 also carries a neck-engaging notched disk 26 which cooperates with the disk 17.

Mesning with gear 23 is a gear 28 which is attached to a shaft 29 carrying a bottle-receiving horizontal disk 30. Suitable guides 31 are arranged in conjunction with disk 30, wheel 25 and disk 15, to cause the bottles B to traverse a serpentine path in the usual well-known manner, this path coinciding in part with the circular path of capping plungers 19.

A cap feeding chute 32 with associated cap controlling mechanism, which forms no part of my present invention, is suitably arranged to deliver caps to the bottles before they reach that point in their serpentine path which coincides with the path of plungers 19.

Thus far the structure may be of standard construction, although in the present drawings, this construction varies in some details from standard.

In prior constructions, a spring-pressed cam 40 has been provided to operate in conjunction with the cam track 21, and so arranged that after a bottle and its associated cap have been brought into alignment with the path of movement of the capping plungers 19, said plungers will be brought successively into engagement with said cam and be thereby depressed upon the associated cap and bottle, the backing spring 41 of said plunger yielding under the resistance of the plunger 19.

In the present construction, I provide, as an abutment for spring 41, a collar 42 which is sleeved upon the stem 40' of cam 40 and is provided with temper screws 43 which

engage a piston 44 mounted in a cylinder 45. Cylinder 45 communicates, through a passage 46, with a reservoir 47 which is arranged above the cylinder.

5 Located in passage 46 is a valve 48 which controls communication between cylinder 45 and reservoir 47. This valve is conveniently an ordinary rotary type having its stem projected through a packing gland 49 and 10 provided with an operating arm 50 to which is connected a pitman 51, said pitman being connected to a crank pin 52 carried by a shaft 53, provided with a gear 54 meshing with a gear 55, to which is connected a bevel 15 gear 56, which meshes with a gear 57 upon the upper end of shaft 11, the arrangement being such that the valve 48 will be rocked, opened and closed in timed relation with the operation of shaft 11 and the timing 20 being such that valve 48 is closed whenever a roller 20 of any plunger 19 reaches the point X (Fig. 4) on cam 40, this point being above the lowest point of the cam by that amount which will give the maximum desired compression of spring 41. It will, of 30 course, be understood that if no actual yielding of the spring is desired except as a precautionary measure, the valve 48 will not be closed until each plunger 19 has come to a position where its roller 20 is contacting cam 40 at the point Y, this point being a distance above the lowest point of the cam equal to the amount of stroke of plunger 19 35 absolutely essential to crimp the cap upon the bottle. In any case, the closing of valve 48 will take place only when each plunger 19 has reached a definite position in its path of travel.

It will, therefore, be seen that when a tall 40 bottle has been placed beneath a plunger 19, its roller 20 will initially contact cam 40 at an abnormally high point and, as the resistance to upward movement of piston 44 with the valve 48 open, is less than the resistance 45 of the cap upon the bottle, cylinder 44, and, consequently, the spring abutment 42 will readily yield upwardly until valve 48 is closed, whereupon, further upward movement of the cylinder 44 is prevented and, 50 consequently cam 40 is in position to offer just the right amount of resistance to the plunger to cause a crimping and setting of the cap, this crimping and setting action being uniform, irrespective of the height of 55 the bottle. It will, of course, be understood that cylinder 45 and a portion of reservoir 47, is preferably filled with a non-compressible liquid, such as oil.

In order to prevent ejection of the oil 60 from reservoir 47, I prefer to protect the air vent 60 with a splash skirt 61.

It will be understood from what has been said that by an accurate adjustment of the mechanism so that valve 48 is closed at 65 exactly the right moment, there is no need

of the abutment spring 41, except when, through accident, a bottle is presented to the capping mechanism without a superimposed cap, because, under normal conditions, the amount of downward movement of the cap 70 upon a bottle in order that it be properly placed, is a uniform amount, irrespective of the height of the bottle which is presented and, consequently, if the timing mechanism is so adjusted that the point X 75 is just exactly the right distance above the lowermost point of the cam 40, the cap will be positioned at just the moment when the fluid, against which piston 44 is acting, becomes immobile. 80

It is, however, desirable, in case of non-placing of the cap, to prevent the splintering of the bottle and, instead of the yielding spring 41, the construction shown in Fig. 6 may be utilized. In that construction, the parts 44-57, inclusive, are the same as in the construction shown in Fig. 1. The stem 40' of cam 40, however, is connected directly to piston 44. Leading from the upper end of cylinder 45 is a bypass 90 which leads to supply chamber 47, and in this bypass, I arrange an outwardly-opening valve seat 91, upon which is seated an outwardly-opening valve 92 normally held to its seat by spring 93, the tension of which may be 95 adjusted by the adjustable abutment 94.

In this construction, the timing mechanism operating valve 48 will operate as previously described, and the fluid within cylinder 45 is then backed up by a spring 93 100 and valve 92. If the operation of the parts is normal, there will be no yielding of the valve 92, but if, as in case of a non-placement of a cap, the non-yielding of cam 40 would operate to crush the bottle, it is apparent that the initial pressure tending to 105 this crushing, would exceed the resistance of spring 93, whereupon valve 92 would yield to permit a sufficient amount of oil to pass upwardly through bypass 90 into 110 chamber 47, this surplus flowing back through valve 48 when the timing mechanism is operated to open the valve.

I claim as my invention:

1. A package capping machine, comprising 115 means for carrying the packages successively through capping position and supporting the same relatively stationary, cap-engaging means, an abutment having variable opposition positions for said cap-engaging means, and means in timed relationship with the package-carrying means for holding said abutment in any of its variable positions in opposition to the cap-engaging means. 120

2. A package capping machine comprising 125 means for carrying packages in succession through a capping position and supporting the same relatively stationary, cap-engaging means coordinated with said cap- 130

ping position, a variable abutment for said cap-engaging means, a fluid container associated with said abutment, and means in timed relationship with the package carrying means for controlling fluid flow with relation to said container.

3. A package capping machine comprising means for carrying packages in succession to a capping position, a cap-engaging plunger, means for carrying said cap-engaging plunger through the capping position, a cam engaged by said plunger as it passes through the capping position, an abutment for said cam, a fluid container associated with said abutment, a valve for controlling fluid flow with relation to said container, and means synchronized with the package-carrying means for opening and closing said valve.

10 4. A package capping machine comprising means for carrying packages in succession to a capping position, a cap-engaging plunger, means for carrying said cap-engaging plunger through the capping position, a cam engaged by said plunger as it passes through the capping position, an abutment spring for said cam, a yielding abutment for said spring, a fluid container associated with said yielding abutment, a valve for controlling fluid flow with relation to

15 said container, and means synchronized with

the package-carrying means for opening and closing said valve.

5. A package capping machine, comprising means for carrying the packages successively through capping position, cap-engaging means, an abutment having variable opposititon positions for said cap-engaging means, means in timed relationship with the package-carrying means for holding said abutment in any of its variable positions in opposition to the cap-engaging means, and a yielding abutment associated with said variable abutment to yield under excessive pressure acting upon the cap-engaging means.

6. A package capping machine comprising means for carrying the packages successively through capping position, cap-engaging means, a variable abutment for said cap-engaging means, a fluid container associated with said abutment, an outwardly-opening valve leading from said container, a yielding abutment for said valve, a passage leading from the discharge side of said valve to an inlet passage leading back into the container.

In witness whereof, I have hereunto set my hand at Indianapolis, Indiana, this twenty-second day of October, A. D. one thousand nine hundred and twenty.

EDWARD F. EDGEcombe, Jr.
